DESIGN FOR A PHYSICIAN'S EXAMINING TABLE

Henry J. Kalter, New York, N. Y.

Application June 14, 1935, Serial No. 57,259

Term of patent 7 years

To all whom it may concern:

Be it known that I, Henry J. Kalter, a citizen of Austria and residing in New York, county of Bronx, and State of New York, have invented a new, original, and ornamental Design for a Physician's Examining Table, of which the following is a specification, reference being had to the accompanying drawing, forming part thereof.

I claim:

The ornamental design for a physician's examining table, as shown.

HENRY J. KALTER.
